LINN BRADLEY, OF MONTCLAIR, NEW JERSEY, AND EDWARD P. MCKEEFE, OF NEW YORK, N. Y., ASSIGNEES TO BRADLEY-MCKEEFE CORPORATION, OF NEW YORK, N. Y., A CORPORATION OF NEW YORK.

PRODUCTION OF ALKALI-METAL CARBONATES.

No Drawing. Application filed November 5, 1921, Serial No. 513,161. Renewed May 20, 1927.

This invention relates to improvements in the production of alkali-metal carbonates, and it includes an improved method of producing alkali-metal carbonates from alkali-metal sulfites as well as from certain products resulting from the treatment of alkali-metal sulfites.

The invention is based upon the discovery that when an aqueous solution of normal sodium sulfite (Na_2SO_3) is heated with cellulose-bearing materials, for example such as wood, for the production of pulp from the wood, there is produced a liquor which, upon evaporation and incineration, will under certain conditions yield a product which contains the greater part of the sodium of the original sodium sulfite, in the form of sodium carbonate.

The invention will be further illustrated by the following more detailed description, but it is intended and will be understood that the invention is illustrated by but is not limited to the specific examples thus described.

An aqueous solution of normal sodium sulfite (Na_2SO_3) is cooked or digested with chipped wood, for example, poplar, birch or spruce wood or other coniferous or deciduous wood, using about 30%–40% or even larger amounts of the sodium sulfite (Na_2SO_3) based on the air-dried weight of the wood, and using a sufficient amount of water so that the wood chips are covered by the sodium sulfite solution. The digestion may be carried out by heating the liquor and chips by means of direct steam at a steam pressure varying from about 110 to 140 pounds (although lower or higher pressures may be used), and the digestion can be continued for a suitable period of time, for example, from ten to three hours, depending upon the wood, temperature and other factors, as will be understood by those familiar with the art, or until the wood fibres are substantially freed from non-fibrous constituents. As a result of the digestion above described, the cellulosic material itself is converted into a high grade pulp suitable for paper manufacture, etc. which is thus produced as one of the valuable products of the complete process.

The residual liquors produced by the digestion above described will contain large amounts of organic compounds, a greater or less portion of which may be sodium-organic

compounds or sodium-sulfo-organic compounds. The liquor may also contain unchanged sodium sulfite as well as other products. These liquors have a characteristic composition and they seem to contain considerable amounts of organic acids or readily oxidizable compounds, which, on oxidation, yield organic acids. These organic acids or acid compounds, when the liquor is concentrated and evaporated to dryness and incinerated in the presence of air, seem to react upon the sodium sulfite of the solution and other sulfur-containing compounds so that the greater part of the sulfur dioxide of the sodium sulfite initially employed is set free and driven off, especially when the evaporation, drying and incineration operation is conducted in the usual rotary furnace commonly used in the soda process.

The evaporation of the solution may be carried out in different ways. The solution may, for example, be evaporated in a multiple effect evaporator until it has a specific gravity of about 40–60° Tw. and the concentrated liquor then fed into a rotary furnace such as is commonly used in the calcination and incineration of concentrated black liquor produced by the soda pulp process. The rotary furnace may be heated, for example, by means of a coal fire at the lower end, that is, at the discharge end, and the hot gases from the furnace may be utilized for heating or the generation of steam in a boiler. The furnace gases in such a furnace so heated will contain nitrogen and oxygen and will promote the removal of sulfur compounds from the material undergoing incineration.

The product resulting from the evaporation and incinerating operation may contain the greater part of the sodium of the original sodium sulfite as sodium carbonate, and the sodium carbonate can be recovered, for example, by leaching with water and by concentration of the resulting solution, the solution being treated or purified by any usual means.

While we do not desire to limit ourselves by any theoretical explanation of the action which takes place in the process of the present invention, nevertheless we believe that the action of the sodium sulfite upon the non-cellulose constituents of the wood results in the production of complex products, includ-

ing probably considerable amounts of acids or acid-forming compounds as well as sodium salts of some of such compounds; and these acids or acid-forming compounds appear to 5 drive off sulfur dioxide from its combinations with soda and perhaps from its combination with organic substances, so that the sodium of the sodium sulfite originally used is, at the end of the drying operation, or after 10 preliminary calcination, present mainly if not entirely as sodium organic compounds or sodium salts of organic acids, which, upon incineration, are decomposed so that sodium compounds are converted into sodium carbonate. The sodium carbonate thus produced may, however, be admixed with varying amounts of other sodium salts, and including even sulfur-containing sodium compounds. 15

20 The sodium carbonate thus produced may be obtained in a solid state and may be further purified if desired.

By carrying out the calcination or destructive distillation of the dry product (resulting from evaporation) in apparatus provided with means for condensing and recovering volatilized products, such products can be recovered as valuable by-products of the process. 25

30 It will thus be seen that the process of the present invention results in the production of an alkali-metal carbonate, such as sodium carbonate, from an alkali-metal sulfite such as sodium sulfite, by treating a solution of 35 the sulfite with cellulosic material such as wood, and by evaporation of the resulting solution and incineration of the dried product. From another standpoint, the present invention may be considered as an improvement 40 in the treatment of residual liquors from the manufacture of pulp by the cooking of the cellulose-bearing material with a solution of alkali-metal sulfite. That is, the invention may be considered as a method of producing 45 sodium carbonate from such residual liquors of the pulp-making process. Accordingly, we claim the invention both for the production of alkali-metal carbonate from such residual liquors, and as a complete process 50 starting with the alkali-metal sulfite itself and by treating such sulfite in a manner which will give a product from which alkali metal carbonate can be produced, and which will at the same time give a good yield of 55 valuable pulp as one of the products of the complete process.

Instead of using sodium sulfite in the manner above described, potassium sulfite, or a mixture of sodium and potassium sulfites, 60 can be similarly used.

We claim:

1. The process of producing an alkali-metal carbonate from an alkali-metal sulfite which comprises digesting a solution of 65 normal alkali-metal sulfite with cellulose-

bearing materials, separating the resulting liquor from the cellulosic materials and treating the resulting liquor for the production of alkali-metal carbonate therefrom, by evaporating the liquor and furnacing the 70 residue in the presence of a current of hot gases including nitrogen and oxygen and under conditions to drive off a sulfur compound and give a furnace product containing the greater part of the sodium of the original 75 sodium sulfite in the form of sodium carbonate.

2. The process of producing an alkali-metal carbonate from an alkali-metal sulfite which comprises digesting a solution of normal alkali-metal sulfite with wood, separating the resulting liquor from the cellulosic materials, evaporating the resulting liquor and calcining the resulting dry product. 80

3. The method of producing an alkali-metal carbonate from the residual liquor resulting from the cooking of resinous wood with a solution of normal alkali-metal sulfite which comprises evaporating such liquor to dryness and calcining the dry product. 85

4. The process of producing sodium carbonate from sodium sulphite, which comprises digesting wood with a solution of sodium sulphite, separating the resulting liquor from the cellulosic material, concentrating the 95 resulting liquor, subjecting the concentrated liquor to calcination, and dissolving the sodium carbonate from the calcined product. 90

5. The method of producing sodium carbonate from the residual liquor resulting from the cooking of wood with a solution of sodium sulphite, which comprises evaporating such liquor to dryness and calcining the dry products under oxidizing conditions, whereby the sodium compounds of the residual liquor are 100 largely oxidized and converted into sodium carbonate, and extracting the sodium carbonate from the calcined product. 105

6. The process of producing sodium carbonate from normal sodium sulfite, which comprises digesting wood with a solution containing normal sodium sulfite amounting to at least 30% of the air-dried weight of the wood under conditions to give a pulp suitable for paper manufacture, separating the resulting liquor from the fibrous material, subjecting the liquor to evaporation and calcination under conditions to drive off sulfur-bearing material and give a calcined product containing the greater part of the sodium of the original sodium sulfite in the form of sodium carbonate. 110

7. The method of producing sodium carbonate from the residual liquor resulting from the cooking of wood with a solution containing normal sodium sulfite, which comprises evaporating such liquor, feeding the concentrated liquor into a rotary calcining furnace and subjecting it to calcination therein under conditions to give a calcined product containing the greater part of the sodium of the original 125 sodium sulfite in the form of sodium carbonate. 130

nal sodium sulfite in the form of sodium carbonate, and leaching the sodium carbonate from the calcined product.

8. The process of producing sodium carbonate from normal sodium sulfite, which comprises digesting wood with a solution containing at least 30% of sodium sulfite on the air-dried weight of the wood, separating the resulting liquor at the end of the digesting 50 operation, subjecting the same to concentration and calcination under conditions to give a calcined product containing the greater part of the sodium of the original sodium sulfite in the form of sodium carbonate, and 55 leaching the sodium carbonate from the calcined product.

9. The method of producing sodium carbonate and of recovering sulfur dioxide from the residual liquor resulting from the cooking 60 of wood with a solution containing sodium monosulfite, which comprises evaporating such liquor and calcining the evaporated product under conditions to produce sulfur dioxide and to give a calcined product containing the greater part of the sodium of the original sodium sulfite in the form of sodium carbonate, and condensing and recovering volatilized products given off during the calcination.

10. The method of producing sodium carbonate from the residual liquor resulting from the cooking of wood with a solution containing normal sodium sulfite, which comprises evaporating such liquor, feeding the 65 evaporated product into a rotary calcining furnace and subjecting it to calcination therein under oxidizing conditions to give a calcined product containing the greater part of the sodium of the original sodium sulfite in 70 the form of sodium carbonate, sulfur dioxide being produced during the process, and leaching the sodium carbonate admixed with varying amounts of other sodium salts from the calcined product.

11. The process of deriving a carbonate of sodium from sodium monosulfite, which comprises digesting wood with a cooking liquor supplied with sodium monosulfite until a substantial portion of the sodium content of such 75 sulfite is present in the form of sodium organic compounds, separating the resulting residual liquor from the resulting fibrous material, removing water from such residual liquor and furnacing the residue to decompose such sodium-organic compounds and burn organic matter and recovering sodium compounds including sodium carbonate.

12. The process of producing an alkali-metal carbonate from sodium monosulfite, which 80 comprises digesting cellulose-bearing material by means of cooking liquor supplied with sodium monosulfite and continuing the digesting treatment until non-fibrous organic constituents of such cellulose-bearing material have been so digested as to render fibres

thereof readily separable from each other by mechanical treatment and thereby form such a residual liquor as, upon evaporation and incineration in a rotary furnace in such manner as is customarily employed in working up 70 black liquor produced from wood by the conventional soda process, is capable of forming furnace gases which carry a preponderating amount of the sulfur combined with sodium monosulfite when supplied to such a cooking 75 liquor, separating such residual liquor from the resulting fibrous material, removing water from such residual liquor and incinerating the resulting residue under conditions adapted to form furnace gases which carry 80 such a preponderating amount of such sulfur and thus form a furnace product including an alkali-metal carbonate, substantially all of the salts contained in the furnace product being soluble in water.

13. The process of producing a carbonate of sodium from a sulfite of sodium, which comprises digesting wood by means of cooking liquor supplied with about 30% to 40% of sodium monosulfite (Na_2SO_3) based on the 85 air-dried weight of the wood and continuing the digesting treatment until there is produced such a residual liquor as, upon evaporation and incineration in a rotary furnace in such manner as is customarily employed in 90 working up black liquor produced from wood by the conventional soda process, is capable of forming a furnace product including sodium carbonate, separating such residual liquor from the resulting fibrous material, removing water from such residual liquor and incinerating the resulting residue under conditions adapted to form a furnace product including sodium carbonate and under conditions to form furnace gases which carry 95 sulfur-bearing material derived from such residual liquor to such an extent that the greater part of the alkali-metal content of the sodium monosulfite supplied to the cooking 100 liquor is present in the furnace product as 110 sodium carbonate, and substantially all of the salts contained in the furnace product being readily soluble in water.

14. The process of deriving a carbonate of sodium from sodium monosulfite, which 115 comprises digesting wood by means of cooking liquor supplied with sodium monosulfite and continuing the digesting treatment until there is produced such a residual liquor as, upon evaporation and calcination in a rotary 120 furnace in such manner as is customarily employed in working up black liquor produced by digesting wood by the usual caustic soda cooking liquor of the conventional soda process, is capable of yielding a furnace 125 product including sodium carbonate and sodium-sulfur compounds, the sodium content of the former being in excess of the sodium content of the latter, and then separating such residual liquor from the resulting 130

- fibrous material, removing water from such residual liquor and calcining the residue under conditions adapted to form such a furnace product and to form furnace gases 5 which carry sulfur-bearing material derived from constituents of such residual liquor to an extent sufficient to prevent the furnace product carrying more sodium content as sodium-sulfur compounds than as sodium 10 carbonate, and substantially all of the sulfur-compounds in such furnace product being readily soluble in water, and subsequently forming a solution including sodium-sulfur compounds derived from such furnace product 15 and also including a carbonate of sodium.
15. In a process for deriving a carbonate of sodium and a sodium-sulfur compound from sodium monosulfite, the steps which comprise digesting wood by means of cooking liquor supplied with at least about 30% of sodium monosulfite (Na_2SO_3) based on the air-dried weight of the wood, and continuing the digesting treatment until substantially all 20 of the readily digestible non-fibrous organic matter thereof has been digested and there is produced such a residual liquor as, upon evaporation and calcination in a rotary furnace in such manner as is customarily employed in working up black liquor produced 25 by digesting wood by the usual caustic soda

cooking liquor of the conventional soda process, is capable of yielding a furnace product containing in the form of sodium carbonate the greater part of the sodium of the sodium monosulfite and also containing sodium-sulfur compounds, and then separating such residual liquor from the resulting fibrous material, removing water from such residual liquor and calcining the residue under conditions adapted to form such a furnace product, and subsequently forming a solution including substantially all of the sodium and sulfur compounds contained in such furnace product. 35

16. The process of producing sodium carbonate from sodium sulfite which comprises digesting a solution of normal sodium sulfite with resinous wood, the solution containing about 30% to 40% of the sodium sulfite based on the air-dried weight of the wood, and continuing the digestion until the wood fibres are substantially freed from non-fibrous constituents, separating the resulting liquor from the cellulosic materials, evaporating the resulting liquor and calcining the resulting dry 40 product. 50

In witness whereof we have hereunto affixed our signatures.

LINN BRADLEY.
